US0D1066671S

(12) **United States Design Patent** (10) **Patent No.:** **US D1,066,671 S**
(45) **Date of Patent:** **** Mar. 11, 2025**

(54) **CLIP-ON DEVICE**

(71) Applicant: **Kenvue Brands LLC**, Summit, NJ (US)

(72) Inventors: **Max Hunter Knecht**, Brooklyn, NY (US); **Stephen Anton**, Union, NJ (US); **Sean James Coyle**, Pennington, NJ (US); **Nathan Wald**, Summit, NJ (US); **Eleanor F. Small**, Philadelphia, PA (US); **Nicole Kaminsky**, Yardley, PA (US)

(73) Assignee: **Kenvue Brands LLC**, Summit, NJ (US)

(**) Term: **15 Years**

(21) Appl. No.: **29/821,386**

(22) Filed: **Dec. 29, 2021**

(57) **CLAIM**

The ornamental design for a clip-on device as shown and described.

DESCRIPTION

FIG. 1 is a back, right, top perspective view of a clip-on device showing our new design in accordance with a first embodiment;

FIG. 2 is a back, left, bottom perspective view thereof;

FIG. 3 is a front, left, top perspective view thereof;

FIG. 4 is a front, right, bottom perspective view thereof;

FIG. 5 is a back view thereof;

FIG. 6 is a front view thereof;

FIG. 7 is a first side view thereof;

FIG. 8 is a second side view thereof;

FIG. 9 is a top view thereof;

FIG. 10 is a bottom view thereof;

FIG. 11 is a back, right, top perspective view of a clip-on device showing our new design in accordance with a second embodiment;

(Continued)

FIG. 12 is a back, left, bottom perspective view thereof; FIG. 13 is a front, left, top perspective view thereof; FIG. 14 is a front, right, bottom perspective view thereof; FIG. 15 is a back view thereof; FIG. 16 is a front view thereof; FIG. 17 is a first side view thereof; FIG. 18 is a second side view thereof; FIG. 19 is a top view thereof; and, FIG. 20 is a bottom view thereof. The broken lines shown in the figures depict portions of the clip-on device that form no part of the claimed design.

1 Claim, 16 Drawing Sheets
